[57] CLAIM

The ornamental design for a golf tee, as shown and described.

DESCRIPTION

FIG. 1 is a perspective view of a golf tee showing my new design;

FIG. 2 is a first side elevation view thereof;

FIG. 3 is a second side elevation view thereof, the second side elevation view being opposite from the first side elevation view thereof;

FIG. 4 is a third side elevation view thereof;

FIG. 5 is a fourth side elevation view thereof, the fourth side elevation view being opposite from the third side elevation view thereof;

FIG. 6 is a top plan view thereof;

FIG. 7 is a bottom plan view thereof;

FIG. 8 is a perspective view of an alternate embodiment of a golf tee showing my new design;

FIG. 9 is a first side elevation view thereof;

FIG. 10 is a second side elevation view thereof, the second side elevation view being opposite from the first side elevation view thereof;

FIG. 11 is a third side elevation view thereof;

FIG. 12 is a fourth side elevation view thereof, the fourth side elevation view being opposite from the third side elevation view thereof;

FIG. 13 is a top plan view thereof; and,

FIG. 14 is a bottom plan view thereof.
